Term of patent 3½ years

(Cl. D81—10)

FIG. 1 is a front perspective view of an electric space heater embodying my design;

FIG. 2 is a rear perspective view thereof, and

FIG. 3 is an end elevational view thereof.

My design for the electric space heater as disclosed resides in the specific uneven sized end members which have top surfaces tapering slightly from the outer ends upward toward the inner edges, in association with the guard wires arranged as shown between said end members.

I claim:

The ornamental design for an electric space heater, as shown and described.
